UNITED STATES PATENT OFFICE.

DANIEL JOSEPH MEISTER, OF WASHINGTON, DISTRICT OF COLUMBIA.

WATER-HEATING APPARATUS.

1,404,134.

Specification of Letters Patent. Patented Jan. 17, 1922.

Application filed July 1, 1920. Serial No. 393,261.

To all whom it may concern:

Be it known that I, DANIEL J. MEISTER, a citizen of the United States, residing at Washington, District of Columbia, have invented certain new and useful Improvements in Water-Heating Apparatus, of which the following is a specification.

This invention relates to an improved water heating apparatus designed especially for domestic use in connection with stoves or ranges constructed to burn natural or manufactured gas, or any liquid hydrocarbon fuel.

Heretofore it has been customary to install in homes a well-known type of water heater comprising a heating coil enclosed within a casing in which is also arranged a gas burner, the water heated in the coil being delivered to a hot water tank from which it may be drawn as required. Such burners have been constructed so as to produce a relatively large flame and consequently they consume a considerable amount of gas, this amount of gas being in addition to that consumed by the kitchen cooking stove or range.

It is therefore the primary object of the present invention to provide as a substitute for the ordinary coil and its associated burner a water heating apparatus including one or more heating chambers which may be associated directly with the burner or burners of the stove so that the flame produced by the burning of the gas or other fuel supplied to the burner will not only serve to heat the water chamber but also to heat any utensil and its contents which may be disposed above the burner in the ordinary manner. Therefore the invention contemplates a great saving in fuel inasmuch as a single burner, while being employed for the cooking of food stuffs, will serve also as a heating medium for producing a quantity of hot water.

A further object of the invention is to provide an apparatus of the general description given above which may embrace and desired number of units or water chambers thus adapting the invention for use in connection with stoves, ranges, or hot plates embodying any number of burners which it may be desired to utilize for the purpose.

50 A further object of the invention is to so construct each unit of the apparatus as to provide for a continuous circulation of water

therein and thereby prevent the accumulation of sediment with a consequent clogging and eventual burning out of the unit. 55

In the accompanying drawings:

Fig. 1 is a perspective view illustrating one embodiment of the invention employed in connection with a gas range;

Fig. 2 is a perspective view of one of the 60 units and the burner with which it is to be associated;

Fig. 3 is a vertical diametric sectional view through one of the units;

Fig. 4 is a view partly in top plan and 65 partly in horizontal section illustrating one of the units.

Each of the heating units above referred to comprises a water chamber 1 which in the present instance is of annular form and circular in cross section as clearly shown in Figs. 3 and 4 of the drawings although it will be understood that this chamber may be of any other open geometrical form such for example as rectangular, triangular, etc. In 70 its outer side the chamber 1 is provided, preferably although not necessarily, at diametrically opposite points, with nipples 2 and 3 into which may be fitted the ends of water inlet and outlet pipes indicated respectively by the numerals 4 and 5. The chamber is provided with any suitable number of legs or brackets 6 which preferably project radially from the outer side thereof and which may be of any desired form to 75 adapt their outer or lower ends to rest upon or be connected with the open top or grate 7, of the stove, which lies above the burner indicated by the numeral 8. This burner is of the ordinary type and at this point it may be 80 stated that the apparatus may comprise but a single one of the units or a plurality of the units in which latter event the units will be connected up in any desired manner, one example being illustrated in Fig. 1 of the 85 drawings. The number of units will depend upon the number of burners which are to be utilized in connection with the apparatus of the invention and it will be understood that one unit is to be placed above each of such 90 burners. Ordinarily the burners of a gas stove or range are of the annular form illustrated in Fig. 2 of the drawings and it will be preferable to so position the unit 1 that

the annular water chamber thereof will be located directly above and in spaced relation to the annular body of the respective burner so that the said chamber will be in position 5 to have the flames from the burner impinge thereagainst.

Each unit comprises, in addition to its annular water chamber, a plurality of water tubes indicated in general by the numeral 10 9. These tubes are united as for example by welding, to the water chamber at the inner side of the latter and project radially inwardly as clearly shown in Figs. 2 and 4 of the drawings, the tubes at their ends 15 which connect with the water chamber being open and placed in communication with the interior of the said chamber by openings 10 formed in the said inner side of the chamber. Each of the water tubes 9 is divided 20 by a diametric and longitudinally extending partition 11 which terminates at its inner end short of the adjacent end of the water tube 9 which is closed as at 12, so as to form a by-pass passage 13. The partition 11 is 25 horizontally disposed and consequently divides the interior of the respective water tube into an upper passage 14 and a lower passage 15. The said partition likewise divides the opening 10 so that water heated 30 within the annular water chamber will flow along the passage 15, through the by-pass 13, into the passage 14, and thence back into the water chamber. In this manner a continuous circulation of water is set up and 35 maintained while the apparatus is in use and therefore sediment is prevented from accumulating within the water tubes and the water chamber. Each chamber may be provided with any desired number of water 40 tubes and the tubes may be arranged in any manner found most desirable, and inasmuch as they project radially inwardly from the inner side of the chamber, they too will be subjected to the flames from the burner. 45 The partitions 11 may be secured in place in any suitable manner and for this purpose the open end of each water tube may be notched at diametrically opposite points as at 16 and the corresponding end of the partition may be struck out to provide portions 50 17 engaging in the notches.

Fig. 1 of the drawings illustrates one manner in which the apparatus of the present invention may be installed and in this figure 55 the numeral 18 indicates in general an ordinary gas range above the burners of which are disposed the several units of the apparatus. The numeral 19 indicates a cold water supply pipe which may be provided 60 with a cut-off valve 20 and this pipe communicates with or is equivalent to the inlet pipe 4 heretofore described and consequently supplies cold water to one of the heating units. When the burners are lighted the 65 water heated in this unit will pass through

the other units and finally out through a pipe 21 which may correspond to the pipe 5 heretofore referred to. The said pipe 21 discharges into the upper portion of a hot water storage tank 22, and cold water from 70 the bottom of this tank is led by a branch 23 to the pipe 19 so as to maintain a constant circulation through the system. Of course, so long as there is an adequate supply of water within the storage tank 22, the valve 75 20 may remain closed but the supply may be replenished at any time by opening this valve. In order that the quantity of water within the tank may be ascertained at a glance, a water gage 24 is provided in connection with the tank. Hot water is to be drawn off from the tank through a pipe 25 which extends into the tank preferably through the top thereof and downwardly beside the tank, being provided at its lower 80 85 end with a suitable spigot 26.

In the claims I will refer to the water chamber comprising the heating unit as of annular form but I intend that this term shall be taken in its broadest sense so as 90 to include any chamber of open or ring like form whether it be annular, rectangular, triangular, or of any other geometrical configuration.

It is preferable that the member 7 be provided upon its upper side with a number of small supporting lugs indicated by the numeral 7' which lugs will serve to support the bottom of the cooking utensil, disposed thereon, spaced a suitable distance above the 100 upper side of the said member 7 so as to permit of the ready passage of heated air currents about the bottom and sides of the said utensil.

Having thus described the invention, what 105 is claimed as new is:

1. The combination with a fuel burner having a stationary top; of a chambered ring-shaped member having inlet and outlet ports adapted for connection with a water 110 circulating system, said member being provided with centerward extending tubular fingers closed at their extreme ends and opening into the chamber of said member and there provided with a pair of notches 115 at their horizontal diameter, a horizontal partition inserted in each finger extending short of said closed end and constructed to engage said notches; knee-shaped legs integral with said member and projecting 120 radially therefrom and extending below said member in order to support the member upon said top and in spaced relation thereto.

2. The combination with a fuel burner having a stationary top; of a chambered ring-shaped member having inlet and outlet ports adapted for connection with a water 125 circulating system, said member being provided with centerward extending tubular fingers closed at their extreme ends and 130

opening into the chamber of said member and there provided with a pair of notches at their horizontal diameter, a horizontal partition inserted in each finger extending short of said closed end and constructed to engage said notches; knee-shaped legs integral with said member and projecting radially therefrom and extending below

said member in order to support the member upon said top and in spaced relation 10 thereto, said member also having lugs of uniform height upon its upper side adapted to contact with the bottom of a cooking utensil.

In testimony whereof I affix my signature.

DANIEL JOSEPH MEISTER. [L.S.]
